UNITED STATES PATENT OFFICE.

ORLANDO S. WATTS, OF CAMDEN, NEW JERSEY.

STENCIL-CUTTING MACHINE.

1,305,847.

Specification of Letters Patent. Patented June 3, 1919.

Application filed March 8, 1918. Serial No. 221,224.

To all whom it may concern:

Be it known that I, ORLANDO S. WATTS, a citizen of the United States, residing at 766 Line St., Camden, in the county of Camden and State of New Jersey, have invented new and useful Improvements in Stencil-Cutting Machines, of which the following is a specification.

The invention relates to stencil-cutting machines, and more particularly to machines which operate in the nature of a typewriter, to cut stencils which may later be used for form letters, notices, circulars and the like.

The invention is particularly adapted to a typewriting machine, and to this end consists more particularly in an attachment for a typewriting machine, whereby with the use of the attachment it will be possible to make the typewriting machine more efficient 20 in the cutting of stencils.

Although I may particularly adapt my stencil-cutting attachment to a Hammond typewriter, a type of machine that is well known in the trade, it will be understood 25 that I may adapt the attachment to various other forms of typewriting machinery and may, if desirable, construct a machine along the lines of my invention which will be particularly adapted to stencil cutting.

In the further disclosure of the invention, reference is to be had to the accompanying drawings, constituting a part of this specification, in which similar characters of reference denote corresponding parts in all the 35 views, and in which—

Figure 1 is a fragmentary elevation showing my device applied to a typewriting machine, parts being shown in section to disclose the underlying structure.

Fig. 2 is a fragmentary vertical sectional view taken on the line 2—2 in Fig. 1, and

Fig. 3 is a fragmentary plan view taken on the line 3—3 in Fig. 1.

Referring more particularly to the views, the numeral 10 indicates what may be termed the traveling carriage frame of a typewriting machine, that is to say, the frame which, as is well known, travels back and forth with the carriage and roller of the type-

writer. As mentioned heretofore, I particularly employ my device with a Hammond typewriting machine, one reason therefor being that the paper-holding drum of a Hammond typewriting machine is hollow and in which my attachment can be readily placed. For instance, I provide a trough 11 which is adapted to contain a suitable fluid 12 used in connection with a stencil sheet 13, the fluid being generally known in the trade as dermax fluid, and the trough 11 is arranged in the usual paper-holding roller 14 of a Hammond typewriting machine. Within this trough there is arranged to turn a cylinder 15, journaled by means of suitable studs 16 to the carriage 10 of the machine, the studs carrying suitable operating knobs 17 on their ends, so that the cylinder 15 can be rotated within the trough. The cylinder 15 is provided with a longitudinal slot 18 to permit of the reception of an apron 19 carrying on its inner end a rod 20 to which the apron is attached, the rod 20 being larger than the slot 18 so that the inner end of the apron will be attached and held on the cylinder 15. By rotating the cylinder 15 it will be clear that the apron will be substantially wound around the same, as shown. The stencil sheet 13 is attached to the end of the apron 19 by suitable pins or other fastening devices 21, and it will be clear that when the stencil sheet is wound up on the cylinder, it will be wound around the wound-up apron, and therefore coming in contact with the dermax fluid in the trough, both sides of the stencil sheet will be subjected to the action of the fluid, and later when the stencil sheet is in an extended position, the apron will tend to keep the stencil sheet in a moist and proper condition for stenciling. Rising from the frame 10 and attached thereto is a supplementary frame 22 consisting of a bracket 23 on each side, said bracket having a slot 24 in which operates a thumb screw 25 attached to the lower end of a rod 26, the upper end of which is attached to a bearing 27 or shaft 28. With this construction it will be seen that the shaft 28 can be lowered or raised relative to the carriage, by means

of the thumb screw 25 sliding on the plate or bracket 23, and that one of the supplementary frames 22 is arranged on each side of the carriage frame to support the shaft 28 in a horizontal position. Spools 29 are keyed to the shaft 28 and cords or elastics 30 are wound around the spools with their free ends secured thereto, the other ends of the cords or elastics being adapted for suitable connection with the upper end of the stencil sheet 13, by providing bayonet slots 31 in the stencil sheet in which buttons 32 on the ends of the cords or elastics are attached, said bayonet slots receiving the buttons, as shown. In this manner the stencil sheet can be held in tension, as will also be clearly seen by referring to the views.

A pawl and ratchet mechanism 33 is arranged upon the shaft 28 by having the ratchet, indicated by the numeral 34, keyed to the shaft and the pawl 35 mounted on the supplementary frame, thus preventing reverse movement of the shaft 28. The shaft 28 also carries a pulley 36, and a similar pulley 37 is secured on one of the studs 12 with a chain or belt 38 connecting the pulleys 36 and 37, so that the rotation of the cylinder 15 will bring about rotation of the shaft 28, thus exerting a pull on the stencil sheet to hold the same in tension when the machine is operated to rotate the cylinder 15. Or the cylinder 15 may be geared direct to the usual type roller and actuated thereby, as will be obvious.

With the form of construction described, it will be clear that when this device is used in connection with a typewriting machine, as mentioned heretofore, the typewriter keys are operated in the usual manner to cut the stencil and do the necessary stenciling, the sheet being kept in proper condition by the dermax fluid in the trough, as mentioned heretofore, and it will be seen that when the carriage frame reaches the end of its movement and is returned to initial position, the rotation of the paper roll will bring about the rotation of the shaft on the upper part of the supplementary frame, whereby the stencil sheet will be advanced upwardly one or two spaces, as the case may be, and at the same time unroll a corresponding length of the stencil sheet from the cylinder 15. The tension of the stencil sheet will, by this arrangement, together with the winding up of the cords or elastics 30 on the spools 29, remain practically the same.

A structure of this character used in connection with a typewriting machine as an attachment thereof, enables stenciling to be accomplished in a very economical manner, and by having the trough 11 with the dermax fluid therein, the arrangement of the stencil sheet by connection with the apron

and the sliding of the apron under the cylinder, can be accomplished without soiling the hands with the dermax fluid. Further, the stencil sheet can be moistened any number of times without removing the same from the machine, this being accomplished by simply reversing the movement of the stencil sheet in the machine. Another advantage will be, that the simple arrangement of the device and the confinement of the dermax fluid, will prevent gumming of the mechanism of the typewriting machine, and the dermac fluid will be supplied from the reservoir to the stencil as needed, thus preventing the stencil from getting dry along the working part. As in the nature of a visible typewriting machine, the stencil will also be open to inspection at all times and will be visible to the operator, and by confining the dermax fluid in the trough, the fluid can be used over again after a stencil has been completed.

It will of course be understood that I may use any preferable form or kind of stencil sheet to accomplish the desired result, and that although I have shown a particular form of my machine, various slight changes may be made without departing from the spirit of the invention, the scope of which is defined in the appended claims.

I claim—

1. In combination with a typewriting machine and the traveling carriage frame thereof, a fluid-containing trough movable with the carriage frame, a rotatable cylinder in said trough, an apron connected to said cylinder and adapted to be wound or unwound thereon, a stencil sheet, means for connecting the stencil sheet to the apron, a supplementary frame, means on the supplementary frame and connecting with the stencil sheet to hold the same in tension, means for adjusting the supplementary frame relative to the carriage frame, and means connecting with the supplementary frame to insure a continued tension on the stencil sheet, when the stencil sheet is advanced by the action of the typewriting machine in returning the carriage frame to initial position.

2. In a stencil-cutting device, the combination with a typewriting machine and the movable carriage frame thereof, of means for supporting a stencil sheet in stenciling position on the carriage frame, and advancing said sheet relative to the carriage frame, means for subjecting the stencil sheet to the action of a fluid, a supplementary frame movable with the carriage frame, and means operable with the supplementary frame and connecting with the stencil sheet to hold the stencil sheet in tension, when the latter is advanced relative to the carriage frame.

3. A stencil device comprising a fluid-containing trough, a rotatable cylinder in said trough, an apron around said cylinder, means for removably holding the apron in connection with the cylinder, a stencil sheet for connection with the apron to come in contact therewith, whereby the fluid in the trough will act upon the stencil sheet, a

supplementary frame, tensioning means on the supplementary frame and connecting with the stencil sheet, and means for insuring unwinding of the stencil sheet relative to said cylinder and the retention of the tension thereon.

In testimony whereof I affix my signature. 15
ORLANDO S. WATTS.
